Primary Examiner — Kevin K Rudzinski*Assistant Examiner* — Paul D Bohannon(57) **CLAIM**

The ornamental design for a shawl, as shown and described.

DESCRIPTION

FIG. 1 is a front view of a shawl showing my new design;

FIG. 2 is a rear view of the shawl;

FIG. 3 is a left side view of the shawl, a right side view being a mirror image thereof;

FIG. 4 is a top view of the shawl, a bottom view being a mirror image thereof;

FIG. 5 is a front view of the shawl in use; and,

FIG. 6 is a front view of the shawl in use in an alternative position.

The broken lines in FIGS. 5 and 6 are for are for the purposes of illustrating environmental structure and form no part of the claimed invention.

1 Claim, 4 Drawing Sheets(56)
